United States Patent Office

Des. 181,022
Patented Sept. 17, 1957

181,022

EARRING OR SIMILAR ARTICLE

Fred W. Reis, Irvington, N. J.

Application July 2, 1956, Serial No. 42,100

Term of patent 14 years

(Cl. D45—9)

FIG. 1.

FIG. 2.

FIG. 3.

FIG. 4.

Figure 1 is a front view of an earring or similar article showing my new design with the rotatable elements in a partially opened position;

The dominant features of my design reside in the portion shown in full lines.

I claim:

The ornamental design for an earring or similar article, as shown and described.
